H. E. SWANSON.
RAIL JOINT.
APPLICATION FILED JAN. 30, 1920.

Patented Nov. 30, 1920.

Inventor:

Henry F. Swanson,

By

P. Eugene Talbert

Attorney

UNITED STATES PATENT OFFICE.

HENRY E. SWANSON, OF SAYBROOK, ILLINOIS.

RAIL-JOINT.

1,360,697.

Specification of Letters Patent. Patented Nov. 30, 1920.

Application filed January 30, 1920. Serial No. 355,263.

To all whom it may concern:

Be it known that HENRY E. SWANSON, a citizen of the United States of America, residing at Saybrook, in the county of McLean 5 and State of Illinois, has invented new and useful Improvements in Rail-Joints, of which the following is a specification.

The object of the invention is to provide a joint for railway track rails whereby provision is made for expansion and contraction due to variations of temperature while maintaining such a relation between the connected rail ends as to prevent sagging or disalignment incident to superposed weight, 15 or vibration, even when the rail ends are not directly supported by the ties, and to this end the invention consists in a construction and relation of parts of which a preferred embodiment is shown in the drawing, wherein:

Figure 1 is a perspective view of the adjacent portions of two rail ends and their related fish plates, showing the parts separated.

Fig. 2 is a side view showing the parts in their normal or operative relations.

The adjacent portions of two rail ends to be connected to form a joint are indicated respectively at 10 and 11, it being understood 30 that the opposite ends of each rail section or length are adapted to be constructed respectively as shown at 10 and 11 to the end that the complementary ends of any two rail sections or lengths may be united in the laying 35 of a continuous track, each of said rail ends being divided longitudinally and horizontally in a plane through the web 12 and between the planes of the head 13 and base 14 to form the wings 15 and 16 which when 40 joined and arranged in a common plane as indicated in Fig. 2 combine to form a composite web which corresponds with the rail web throughout the major portion of its length. The flange member 15 is thus 45 formed on the extension of the base 14 of one rail end while the flange portion 16 is formed on the head extension 11 of the other rail end, and the angular fish plates 17 and 18 are adapted for arrangement upon opposite sides of the plane of the rail webs, as 50 in the ordinary practice and are secured in place by bolts 19 extending through registering openings 20 in the fish plates and 21 in the web 12 and flange portion 15.

Also the inner surface of the fish plate 17 55 is preferably provided with a projection 22 formed for example as a rib for engagement with a depression 23 formed as a groove in the side surface of the flange portion 16 which depends from the head extension of 60 the rail end 11 to aid in supporting said head extension and strengthening the joint to prevent displacement under the heavy traffic conditions to which joints of this kind are subjected in practice.

The rib 22 and the corresponding groove or seat 23 may extend for a considerable distance back of the cut-away portion of the rail end 11 so as to effectively reinforce the joint and to guard against any tendency 70 to displacement. Also it will be understood that the fish plates have bearings at their base and upper edges respectively against the base and under surfaces of the rail end heads to add to the rigidity of the joint.

What is claimed is:

1. A rail joint having aligned rail ends respectively divided on a longitudinal horizontal plane intersecting the web and disposed in overlapping relation, and fish plates 80 spanning the overlapped portions of said rail ends in contact with opposite sides of the rail end webs, one of said fish plates having an interlocking engagement with the rail end web which carries the rail head extension.

2. A rail joint having spliced rail ends united on a longitudinal plane intersecting the rail web and providing complementary flange portions projecting respectively from 90 rail head and rail base extensions and combining to form a continuation of the rail end webs, and angular fish plates arranged upon opposite sides of the rail end webs between the heads and bases of the latter and secured by transversely extending bolts, one of said fish plates being provided with a longitudinal rib arranged in interlocking relation with a corresponding groove in the surface of the flange portion which depends 95 from the rail head extension of one of said rail ends.

In testimony whereof he affixes his signature.

HENRY E. SWANSON.
